UNITED STATES PATENT OFFICE.

HAROLD K. GREEN AND JAMES W. JENNINGS, OF PROVIDENCE, RHODE ISLAND.

DESIGN FOR A VASE.

Application filed March 28, 1927. Serial No. 21,381. Term of patent 14 years.

To all whom it may concern:

Be it known that we, HAROLD K. GREEN, a citizen of the United States, residing at Providence, in the county of Providence and State of Rhode Island, and JAMES W. JENNINGS, a citizen of the United States, residing at Providence, in the county of Providence and State of Rhode Island, have invented a new, original, and ornamental Design for a Vase, of which the following is a specification, reference being had to the accompanying drawings, forming part thereof.

Fig. 1 is a front elevation of the vase showing our new design, and

Fig. 2 is a section on line 2—2 of Fig. 1.

We claim:

The ornamental design for a vase, as shown.

In testimony whereof we have signed our names to this specification.

HAROLD K. GREEN.
JAMES W. JENNINGS.
